UNITED STATES PATENT OFFICE

LEONARD G. GRAY, OF DECATUR, ILLINOIS

DESIGN FOR A TILE COUNTER

Application filed January 22, 1932. Serial No. 42,587. Term of patent 7 years.

To all whom it may concern:

Be it known that I, LEONARD G. GRAY, a citizen of the United States, residing at Decatur, in the county of Macon and State of Illinois, have invented a new, original, and ornamental Design for Tile Counters, of which the following is a specification, reference being had to the accompanying drawing, forming part thereof.

The figure is a perspective view of a tile counter showing the new design.

The drawing is shaded to represent contrasting colors.

I claim:

The ornamental design for a tile counter, as shown and described.

LEONARD G. GRAY.
